UNITED STATES PATENT OFFICE.

THOMAS J. STEARNS, OF BOSTON, MASSACHUSETTS, ASSIGNOR TO ROXBURY CARPET COMPANY, OF SAME PLACE.

DESIGN FOR CARPETS.

SPECIFICATION forming part of Design No. 11,720, dated April 6, 1880.

Application filed January 30, 1880. Term of patent 3½ years.

To all whom it may concern:

Be it known that I, THOMAS J. STEARNS, of Boston, in the county of Suffolk and State of Massachusetts, have invented a new and original Design for Carpets, of which the following is a specification.

The nature of my design is fully shown in the accompanying photographic illustration.

The design is composed of the angular figures E D C E' E, &c., arranged and repeating to form continuous diagonal rows, the angular figures A F B, arranged at one side of each row, continuous diagonal ground-spaces S, separating the diagonal rows, and various free-hand floral designs ornamenting said figures and spaces.

This design differs from my designs patented, respectively, March 12, 1878, No. 10,530, and March 26, 1878, No. 10,606, in the arrangement of the figures and in the character of the

floral ornamentation, which, in said patented designs, is almost wholly conventional, while in this design it is entirely free-hand.

I claim—

The design for a carpet, comprising the angular figures E D C E', arranged and repeating to form continuous diagonal rows, the angular figures A B F, arranged at one side of each row, the continuous diagonal spaces S, separating the diagonal rows, and the free-hand floral designs ornamenting said figures and spaces, substantially as shown.

In testimony whereof I have signed my name to this specification, in the presence of two subscribing witnesses, this 23d day of January, 35 A. D. 1880.

THOMAS J. STEARNS.
